CLAIM

The ornamental design for a clock configuration, as shown and described.

DESCRIPTION

FIG. 1 is a perspective view of an ornamental design for a clock configuration according to the invention;

FIG. 2 is a front view of an ornamental design for a clock configuration according to the invention;

FIG. 3 is a right side view of an ornamental design for a clock configuration according to the invention;

FIG. 4 is a rear of an ornamental design for a clock configuration according to the invention;

FIG. 5 is a top view at section line 5—5 in FIG. 2 of an ornamental design for a clock configuration according to the invention; and,

FIG. 6 is a top view at section line 6—6 in FIG. 2 of an ornamental design for a clock configuration according to the invention.

The broken line showings throughout the views are for illustrative purposes only and form no part of the claimed design.
